(57) CLAIM

I claim the ornamental design for the compact disk carrying case with matte silver cover, as shown and described.

DESCRIPTION

FIG. 1 is a front view of a disk carrying case with a matte silver cover, showing my new design, the lines on the cover being understood to represent matte silver throughout the views;

FIG. 2 is a right side view thereof;

FIG. 3 is a left side view thereof;

FIG. 4 is a rear view thereof;

FIG. 5 is a bottom view thereof; and,

FIG. 6 is a top view thereof.

The broken lines shown on the bottom of the case in FIG. 5 are understood to represent stitching.
